SHOE STITCHING MACHINE

Christy N. Lestakis, Portland, Oreg.

Application July 25, 1946, Serial No. 686,053

5 Claims. (Cl. 112—187)

1

My invention relates to machines especially adapted to stitch parts of shoes such as the toe caps thereof and has for its main objective the provision of more bobbin thread in the limited space available for the bobbin carrier in such machines.

The space within the toe of a shoe is very limited and as a consequence those parts of a machine which must enter said limited space must of necessity be very limited in size.

That portion of the machine, or arm, which must enter a toe measures about $1\frac{1}{8}$ " wide by 1" deep on machines now in use.

These machines are provided with a cam which in turn imparts an oscillating movement to a lever of the first class the bottom end of which is connected to a rack engaging a pinion secured to the bottom of a circular bobbin carrier having a hook attached to its peripheral surface.

On machines adapted to form a lock stitch, thread from a spool is threaded thru the tension device and needle eye and thread from the bobbin is brought up thru the hole provided for the needle to enter the top of the machine arm.

The machine needle during its reciprocating movement enters this hole in the outer end of the arm carrying thread from the spool with it. Just as the needle starts its upward movement it hesitates for an instant and in so doing causes the thread to loop outwardly from the needle. The hook on the bobbin carrier picks up this loop and before releasing it carries it around to a position to receive the thread from the bottom bobbin in its bight thus forming a lock stitch.

The foregoing operation is well known to all versed in the operation of sewing machines and is recited as preliminary to what follows. It is apparent that the bobbin must be very limited in size. As a matter of fact this bobbin has a capacity of about 10 lineal feet of thread in machines now in use.

As a consequence the bobbin must be replenished often. It seems that the thread always runs out in the middle of a job much to the exasperation of the shoemaker.

I have found a new way to increase the amount of thread that may be carried by a bobbin without increasing the size of the arm of the stitching machine. How I accomplish the above is illustrated in the accompanying drawings and minutely described in the specification.

Fig. 1 of the drawings is a vertical section on approximately the centerline of the arm; Fig. 2 is a horizontal section on the line 2—2 of Fig. 1;

2

Fig. 2A is a fragmental elevational view of the lever shown in section in Fig. 2; Fig. 3 is a plan showing the transfer of the thread loop from one hook to the other; Fig. 4 is a vertical section on line 4—4 of Fig. 2; Fig. 5 is a vertical section on line 5—5 of Fig. 2; Fig. 6 is a vertical section on line 6—6 of Fig. 2; Fig. 7 is a plan view of the bobbin carrier; Fig. 8 is an elevation of the reciprocating loop carrier; Fig. 9 is a vertical section of a needle showing the forming of the thread loop; Fig. 10 is a diagrammatical elevation showing the relation of the thread loop and the bobbin carrier.

Throughout the drawings and the specification similar numerals refer to similar parts.

The drawings are made on a scale twice the size of the finished product in order to more clearly illustrate the relation of the parts without crowding.

20 Since my invention relates to only a small part of the shoe stitching machine mechanism it has been designed for adaptation to machines now in use.

Therefore, in lieu of connecting the customary rack bar of present machines to the cam-operated oscillating lever, I connect my hook bar or loop carrier 2 in the manner shown in Fig. 2. This hook bar 2 is an elongated structure provided at one end with the jaw 3 for connection 25 to the lever 1 and having at the other end a hook-carrying portion 4 hingedly connected thereto by means of the hinge pin 5. The free end of this hinged portion 4 terminates in a hook 6 the structure of which is more clearly shown in Figs. 2 and 8. In these figures it is to be noted that the hook 6 is bifurcated with the divided portions 7 spaced apart for the purpose later to be described.

The arm casing 8 within which the hook bar 2 is reciprocated has its end 9 curved so that the hinged end portion 4 will be deflected to bring the hook 6 to a position to the left and slightly behind the needle 10. This needle 10, shown in Fig. 9, is the same as used in the prior art and is provided with two grooves 11 and 12 positioned diametrically opposite and above the needle eye 13. In practice I position the short groove 12 facing the hinged end portion 4 so that the thread 14 will loop out toward said portion 4 whereby 45 the loop 15 may readily be engaged by the hook 6 whose point 6A is caused to pass close to the needle 10 by the raised portion 16 formed on the inside curved surface 9 of the casing 8. The hinged end portion 4 of the hook bar 2 is kept from moving too close to the needle by

that portion 17 adjacent to and rearward of the hinge pin 5 which portion 17 is shaped to engage the grooved guiding portion 18 of the casing 8 whereby to limit the movement of the hook 6 to a predetermined path during its travel in either direction.

The hook bar 2 is provided with a pin 19 which projects from the upper face 20 of said bar 2 and into an elongated slot 21 formed in the bottom face 22 of an elongated cam bar 23. This slot 21 limits the movement of the cam bar 23 by the reciprocating hook bar 2. This cam bar 23 is positioned above the hook bar 2 and the movement of both bars is limited to a guideway formed by the surface 24 and 25 of the arm casing 8, the guide lugs 26 formed as a part of said casing 8, and the top cover plate 27. The cam bar 23 has a cam arm 28 projecting from one end thereof. This cam arm 28 engages a pin 29 projecting from the top face of a horizontally revolvable disk 30 pivotally mounted on the pin 31 projecting upwardly from the bottom surface 25 of the casing 8. Extending from the peripheral face of the disk 30 is a hook 32 which is so positioned that it will pass between the bifurcated portions 7 of the hook 6 on the hook bar 2.

The forward inoperative or rest position of the cam arm 28 is forward of the pin 29. On the backward movement of the hook bar 2 its pin 19 engages the end 21A of the slot 21 in the cam bar 23 whereby both bars move backwardly simultaneously whereupon the cam arm 28 engages the pin 29 and causes the disk 30 to rotate clockwise.

The various members of the apparatus are positioned and synchronized so that the hook 6 on the hook bar 2 will be in the position (shown in Fig. 3) or radially aligned with the hook 32 on the disk 30. In practice, when the above occurs, the hook 6 will be extending the loop 15 formed by the needle 10 due to its peculiar construction and operation. This extended loop is clearly shown in Fig. 10.

It is apparent that the hook 32 travels $\pi/2$ times the distance the hook 6 travels hence the hook 32 will engage the loop 15 as said hook 32 passes between the bifurcated portions 7 of the hook 6 and carry said loop 15 away and upwardly from the hook 6. This upward movement of the hook 32 will continue until the cam arm 28 passes under and to the rear of the pin 29 on the disk 30. When this point is reached, or at the end of the backward travel of the hook bar 2, the disk 30 is caused to rotate counterclockwise to its former inoperative or rest position thru the action of the spiral spring 33 positioned above the disk 30 with one of its ends fixed in that portion of the pin 31 which projects above the top face of the disk 30 and the other end looped about a pin 34 projecting from the top face of the disk 30. This counterclockwise rotation of the disk 30 is limited and cushioned by a leaf spring 35 one end of which is secured to the casing 8 by the screws 36 as shown in Fig. 2. As the hook 32 moves counterclockwise a tension is held on the loop 15 by the tension apparatus with which all sewing machines is provided. This tension device has not been illustrated but is well understood by those skilled in the art.

On the forward movement of the hook bar 2 the cam arm 28 engages the pin 29 from its rearward side and the portion 28A raises the hook 32 to the dotted position of said hook shown in Fig. 2. When the hook 32 is in this position the loop 15 is readily released whereupon it is shortened in the well known manner by the tension device of

the machine. It is to be noted that at the point of release the loop 15 is to the right of the pointed end 37 of the bobbin carrier 38. A perusal of the drawings, Figs. 1, 2, 7, and 10, will show that the loop 15 can be readily transferred from the left to the right hand side of the bobbin carrier and that the thread 39 coming from the top of the bobbin carrier will be caught in the bight of the loop 15 which is a necessity in the forming of a lock stitch.

This thread 39 is carried on the bobbin 40 positioned within the bobbin carrier 38. This bobbin carrier 38 is formed in two sections 41 and 42 telescoped together when assembled. The engaging portions 43 and 44 are offset to form a smooth exterior surface. The section 41 has a slot 45 which extends beyond the section 42 when the bobbin carrier is assembled so that the end of the thread 39 may be brought to the exterior of the bobbin carrier without threading it thru a hole. The thread 39 is led from the bobbin 40 out thru the bobbin carrier 38 and out thru the needle hole 46 in the top cover plate 27 as is the usual practice. A tension spring 47 is provided on the bobbin carrier section 42 under which the thread 39 is withdrawn.

The bobbin carrier 38 rests in a cradle 48 formed in the bottom surface 25 of the casing 8 and it is further confined in position by the rearward stop 49 and the forward stop 50 both formed integral with the casing 8. The bobbin carrier 38 is loosely confined so that the thread 39 may be freely withdrawn from its bobbin 40 and so that the loop 15 may readily pass under and over said carrier as said loop 15 is moved from the left to the right hand side thereof.

The bobbin used on prior art machines is $5/8$ " in diameter and $1/4$ " between flanges. The bobbin 40 shown in the illustrations is $5/8$ " in diameter and $2\frac{1}{8}$ " between the flanges yet the machine arm casing 8 is narrower than in the prior art machines. The capacity may be further increased by increasing the movement of the operating lever 1.

It is apparent without further illustration that the hook 6 may be made without the bifurcated portions and that the hook 32 may be made with them. It is also apparent that the design and arrangement of parts may be changed and modified over that shown and described hence I do not limit my invention to the exact illustrations and description herein but extend it to all that comes fairly within the scope of the appended claims.

What I claim as new over the prior art follows:

55. 1. In a shoe stitching machine provided with a bobbin carrier, means for transferring a thread loop formed by said machine from one side of the bobbin carrier to the other which includes a reciprocable bar provided with a hook to engage a loop positioned on one side of the bobbin carrier, means for reciprocating the hook bar, a cam bar periodically operable by the hook bar, and means operable by the cam bar to remove a loop from the hook bar hook and to release it on the opposite side of the bobbin carrier.

56. 2. In a shoe stitching machine the combination of, an arm, a needle, adjacent the end of the arm, carrying a thread and operable to form a loop in said thread, an elongated bobbin carrier positioned in the arm, an elongated reciprocable bar positioned on one side of the bobbin carrier having a hinged end portion terminating in a hook, means to guide said hook to a position with respect to the needle to engage a loop formed thereby, means for reciprocating

said bar, a cam bar periodically operable by the hook bar, and means operable by the cam bar to remove a loop from the hook bar hook and to release it on the opposite side of the bobbin carrier.

3. In a shoe stitching machine the combination of, an arm, a needle, adjacent the end of the arm, carrying a thread and operable to form a loop in said thread, an elongated bobbin carrier positioned in the arm, an elongated reciprocable bar positioned on one side of the bobbin carrier having a hinged end portion terminating in a hook, said bar, hinged portion, and arm, having portions adapted to guide said hook to a position with respect to the needle to engage 15 a loop formed thereby, means for reciprocating said bar, a cam bar periodically operable by the hook bar, and means operable by the cam bar to remove a loop from the hook bar hook and to release it on the opposite side of the bobbin 20 carrier.

4. In a shoe stitching machine the combination of, a needle carrying a thread and operable to form a loop in said thread, a bobbin carrier, a reciprocable bar positioned on one side of the bobbin carrier and provided with a hook adapted to engage a loop formed by the needle, means to reciprocate said bar, means having rotative movement and provided with a hook adapted to remove a loop from the hook bar hook and release it on the opposite side of the bobbin carrier, and means operable by the hook bar to periodically cause said rotative movement.

5. In a shoe stitching machine provided with a needle carrying a thread and operable to form a loop in said thread, a bobbin carrier, a bar on one side of the bobbin carrier having a pin projecting therefrom and a hinged end portion terminating in a hook adapted to engage a loop formed by the needle, means for reciprocating the hook bar, a rotatively mounted disk having a pin projecting therefrom and a hook adapted to engage a loop carried by the hook bar and remove it therefrom, a cam bar provided with an elongated slot for the reception of the pin on the hook bar and having a cam arm projecting therefrom for engagement with the disk pin to cause rotative movement of the disk in one direction whereby its hook is operable to engage and remove a loop carried by the hook bar hook, and means to cause rotative movement of the disk in the opposite direction to permit the disk hook to carry the loop to the opposite side of the bobbin carrier and release it.
